UNITED STATES PATENT OFFICE.

CATHERINE FORTNEY, OF CONFLUENCE, PENNSYLVANIA.

DESIGN FOR A DUST-PAN.

SPECIFICATION forming part of Design No. 34,170, dated March 5, 1901.

Application filed February 9, 1901. Serial No. 46,761. Term of patent 14 years.

To all whom it may concern:

Be it known that I, CATHERINE FORTNEY, a citizen of the United States, residing at Confluence, in the county of Somerset and State 5 of Pennsylvania, have produced a new and original Design for a Dust-Pan, of which the following is a specification.

This invention relates to a new and original design for a dust-pan; and the essential 10 feature resides in the design as illustrated in the accompanying drawings, wherein a perspective view of the dust-pan embodying the design is shown.

The design is characterized by a horizontal 15 or flat bottom 1, having sides 2, which are parallel and formed with front curved bevels 3, the sides being at right angles to the said bottom. From the rear terminal of the bottom extends a right-angular back 4, of greater 20 width than the sides 2 and having end right-angular extensions 5 outside of the rear ex-

tremities of the sides, the upper edge portions of the said extensions having rearwardly-directed curved bevels 6, meeting the upper opposite curved portions 7 of the upper edge 25 of the back. The central portion of the upper edge of the back has an angular projection 8, with curved edges 9 converging to a rear-pointed end 10, and in said projection is an opening 11.

Having thus described the invention, what 30 is claimed as new is—

The design for a dust-pan, herein shown and described.

In testimony that I claim the foregoing as 35 my own I have hereto affixed my signature in the presence of two witnesses.

CATHERINE FORTNEY.
